Primary Examiner — Karen S Acker*Assistant Examiner* — Wendy L Arminio(74) *Attorney, Agent, or Firm* — Law Office of Kevin Roe(57) **CLAIM**

The ornamental design for a user contoured stitched fabric, as shown and described.

DESCRIPTION

FIG. 1 is a top-down view of a user contoured stitched fabric showing my new design;

FIG. 2 is a top-down view thereof shown in a position of use on a human figure drawn in broken lines;

FIG. 3 is a bottom right upper isometric view thereof;

FIG. 4 is a top left upper isometric view thereof;

FIG. 5 is a left side isometric view thereof shown in a position of use on a human figure drawn in broken lines;

FIG. 6 is a right side isometric view thereof shown in a position of use on a human figure drawn in broken lines;

FIG. 7 is a upper end upper angled view thereof; and,

FIG. 8 is a bottom end upper angled view of a user contoured stitched fabric.

The broken lines showing a human figure depict environment that forms no part of the claimed design.

1 Claim, 8 Drawing Sheets(56)
